ATTORNEY

UNITED STATES PATENT OFFICE.

LOUIS P. ZIMMER, OF CANTON, OHIO, ASSIGNOR OF TWO-THIRDS TO
LUTHER M. BARRICK AND CHARLES H. BARRICK, OF CANTON, OHIO.

SEWING-MACHINE-ATTACHMENT HOLDER.

SPECIFICATION forming part of Letters Patent No. 770,707, dated September 20, 1904.

Application filed September 3, 1903. Serial No. 171,816. (No model.)

To all whom it may concern:

Be it known that I, LOUIS P. ZIMMER, a citizen of the United States, residing at Canton, in the county of Stark and State of Ohio, have 5 invented certain new and useful Improvements in Sewing-Machine-Attachment Holders; and I do hereby declare that the following is a full, clear, and exact description of the same, reference being had to the annexed drawings, making a part of this specification, and 10 to the figures of reference marked thereon, in which—

Figure 1 is a view showing the frame of a sewing-machine, illustrating my improvement properly attached to the presser-foot bar. Fig. 2 is a transverse section of the presser-foot bar, also showing in section the 15 different parts pertaining to my improved attachment-holder. Fig. 3 is a view showing the bottom or lower end of an ordinary presser-foot bar. Fig. 4 is a view of the thumb-nut. Fig. 5 is a detached top view of a hemmer. Fig. 6 is a detached view of the attaching 20 screw or stud.

25 The present invention has relation to sewing-machine-attachment holders; and it consists in the novel construction hereinafter described, and particularly pointed out in the claim.

30 Similar numerals of reference indicate corresponding parts in all the figures of the drawings.

In the accompanying drawings, 1 represents 35 the presser-foot bar, which is attached to the head 2 of the sewing-machine proper in the ordinary manner, it of course being understood that different attachments of the presser-foot bar 1 are to be provided for different makes of machines, inasmuch as the presser-foot bar within itself forms no particular part 40 of the present invention except that a presser-foot bar is necessary and becomes a necessary element in carrying out the objects and purposes of the present invention.

45 The bottom or lower portion of the presser-foot bar 1 is provided with the screw-threaded aperture 3, which screw-threaded aperture 3 is for the purpose of receiving the screw-threaded portion of the thumb-nut-holding

50 screw or stud 4. In adjusting the thumb-nut-holding screw or stud 4 it is important that it be properly adjusted, so that its attached end will not extend beyond the surface of the presser-foot bar opposite to that from which the screw or stud 4 extends, and in order to 55 provide for this adjustment the convolutions of the screw-threads stop at a point so that when all the convolutions are received in the screw-threaded aperture proper adjustment 60 will be had for the screw or stud 4.

The screw or stud 4 is provided with the head 5, which head is provided with the slot 6, which slot is for the purpose of receiving an ordinary screw-driver to rotate the screw or stud 4, so as to properly attach the same to 65 the presser-foot bar 1.

The screw or stud 4 is provided with the smooth or non-screw-threaded portion 7 and is so formed for the purpose hereinafter described.

70 The head 5 of the screw or stud 4 is provided with a screw-threaded periphery, which screw-threaded periphery is for the purpose of receiving the internal screw-threads of the thumb-nut 8. The thumb-nut 8 is provided 75 with the internal flange 9, which internal flange is so formed that it will form a stop as against the outward movement of the thumb-nut 8 and at the same time allow the thumb-nut to move back and forth upon the head 5 80 of the screw or stud 4. In the drawings I have illustrated the flange 9 formed integral with the thumb-nut 8; but it will be understood that this is not absolutely necessary owing to the fact that that portion forming 85 the flange 9 may be made separate and attached to the thumb-nut 8. This is simply mechanical as to whether or not the flange portion is formed integral or separate, as the only object designed to be accomplished is to 90 limit the outward movement of the thumb-nut 8, but at the same time allowing the thumb-nut to move back and forth upon the non-screw-threaded portion 7 of the screw or stud 4 as the thumb-nut is rotated in either 95 direction.

It will be understood that in use various kinds of sewing-machine attachments are to

be connected to the presser-foot—for instance, the hemmer 10—and when said hemmer is not in use an ordinary presser-foot may be attached or a ruffler attachment or the many attachments in common use.

It is well understood that if in the event the convolutions of the screw-threads become jammed by reason of removing or attaching the various attachments difficulty is experienced, 10 and hence the screw or stud 4 is provided with the non-screw-threaded portion 7, which non-screw-threaded portion is located at a point or place where the various attachments are to be attached and clamped, and hence no screw-threads are exposed and there can be no injury no matter how careless the operator may be in removing and connecting the various attachments.

It will of course be understood that the 20 connecting-shank 11 of the hemmer 10 is to be so formed that it will fit the bottom or lower portion of the presser-foot bar 1 and the various attachments for any given machine, such as a Singer, are to have connecting-shanks constructed alike so far as pertains to the attachment to the presser-bar.

As shown in the drawings, the thumb-nut 8 is open at its outer end and is so formed for the purpose of allowing the insertion of

a screw-driver to properly connect the screw 30 or stud 4.

Having fully described my invention, what I claim as new, and desire to secure by Letters Patent, is—

The combination of a presser-bar provided 35 with a screw-threaded aperture at its lower portion, an attachment-shank adapted to fit the presser-bar, a screw provided with a head, said head having a screw-threaded periphery, the stem of said screw provided with a screw-threaded end, and a non-screw-threaded portion located between the head and screw-threaded end portion, a thumb-nut located upon the head of the screw and provided with an internal flange adapted for engagement 45 with the inner face of the screw-head, and the attachment located upon the non-screw-threaded portion of the screw at place of contact between the presser-bar and the thumb-nut, substantially as and for the purpose specified. 50

In testimony that I claim the above I have hereunto subscribed my name in the presence of two witnesses.

LOUIS P. ZIMMER.
